FLUID HEAT EXCHANGER FOR AIR CONDITIONING AND REFRIGERATION SYSTEMS AND THE LIKE

Raymond A. Lo Turco, Wexford, Pa., assignor to
Frick Company, Waynesboro, Pa., a corporation of
Pennsylvania

Filed Sept. 1, 1967, Ser. No. 8,459

Term of patent 14 years

(Cl. D23—153)

FIG. 1

FIG. 2

FIG. 1 is a perspective view of the fluid heat exchanger for air conditioning and refrigeration systems and the like according to this invention, and

FIG. 2 is a top plan view of the fluid heat exchanger as shown in FIG. 1.

The dominant features of my design reside in the portions shown in full lines.

I claim:

The ornamental design for a fluid heat exchanger for air conditioning and refrigeration systems and the like, as shown and described.
